TOY

**Nettie Florence Grusenmeyer, San Francisco,
Calif.**

Application January 15, 1944, Serial No. 518,333

3 Claims.

卷之三

My invention relates to animated toys, and particularly to the type which are pulled over the floor by a pull connection.

The object of my invention is to provide a simple, inexpensive, animated toy; to provide a toy which goes through certain antics in the course of its movement from a position of rest to a position of forward movement across the floor and upon the cessation of the forward movement the parts will move by gravity into a position of rest; to provide a toy in which the two elements are pivoted together, the rear element being something which is being pulled by the forward element, and the forward element being representative of some animate thing such as an animal or person; to provide a novel means for connecting together such forward and rear elements so as to introduce a novel coaction between them.

Pursuant to Rev. St. Sec. 4888 I shall describe and illustrate two forms of my invention, but it is not with the intention of limiting my invention to these particular forms or embodiments, except as required by the state of the art and the appended claims.

In the drawing:

Fig. 1 represents a view in vertical elevation of one form of my device:

Fig. 2 represents a top plan view of the device of Fig. 1.

Fig. 3 shows a modification of the device of Fig. 1 employing skids instead of wheels; and

Fig. 4 shows a modification of the wheel mounting.

In the drawing numeral 10 designates a platform mounted on a pair of wheels 11 carried by an axle 12 journaled in the under body 13 of the carriage platform 10. The latter may have any suitable form of body 14 mounted on the platform, or the body 14 may be integral with the platform 10. Likewise the tongue 15 which extends forward from the platform 10 may be integral or a separate piece. Instead of the platform 10 being in the form of a cart or carriage, it may comprise only a single thickness of board which in vertical profile is made to represent some fanciful figure or wagon.

The other unit of my device comprises a vertical member 20 preferably having the vertical side profile of an animate object. I have illustrated my invention with member 20 formed as a rabbit, but any other animal, bird or person might be used. For example, the animated effect obtained with my invention would lend itself very well if the vertical member 20 had the profile of

a tired, lazy colored man. The vertical member 20 has journaled in its base an axle 21 on which are secured the wheels 22. If the vertical member 20 has sufficient thickness a single wheel may be used which would be recessed in the lower body. This is shown in Fig. 4. Between the platform 10 and the vertical member 20 is a pivotal connection 23 on a horizontal axis which will allow for a relative tilting movement of these units with respect to each other. This pivotal connection 23 is aft of the vertical line 24 projected upwardly from the axis 21 of the roller support 22. The reason for this is that I want the normal position of rest of the animal 20 to be that of leaning back against the front of the platform or cart 10. This is obtained by having the relative location of the pivot point 23 and the axle shaft 21 such that the weight on the tongue 15 of the cart will tilt the animal 20 back on its haunches. In Fig. 1, the full line figure of the animal shows it in the back position it assumes when at rest and the dotted line outline shows it when in its forward action position.

25 The animal 20 is pulled up into this position of action by means of a pull connection 30 which may be secured somewhere on the animal 20 as at 31. The location of this point of connection 31 is important for it should lie far enough above 30 the horizontal line 32 projected forward from the axis of the pivotal connection 23, so that a forward pull on the connection 30 will cause the vertical member 20 to tilt forward and change its angular relation to the platform 10. In other 35 words, it will move from the full line into the dotted line position, and then upon release of this forward pull the vertical member will fall back against the platform. To limit the extent of 40 forward tilting of the animal 20 I provide a stop 33 secured to the vertical member 20 and adapted to engage the under side of the tongue 15 when the pull connection 30 has moved the vertical member into its maximum desired forward position.

45 In operation, therefore, it will be seen that if a child should grasp the pull connection 30 and pull forward on it the rabbit 20 will move from the full line into the dotted line position causing the wheels 22 to move from their full line to their dotted line position where the stop 33 fixes the relation of the parts. So long as the child is exerting a pull on string 30 the cart will move forward and will retain this position. As soon as the pull on string 30 is released the rabbit 20
50 will fall back on its haunches, because the weight
55

of the tongue and wagon at the pivot point 23 will overcome any effect of the rabbit 20 to remain erect.

The device shown in Fig. 3 operates on the same principle as the one just described and differs from it only in that the wheels 11 and 22 on the wagon and the rabbit have been replaced with skids 41. The principle of operation is the same because a line 40 projecting downwardly from the pivot point 23 falls aft of the fulcrum point of the skid on the rabbit. Except for this, these structures are identical in principle and operation.

What I claim is:

1. In a wheeled toy the combination of a wagon body having a tongue, wheels beneath said body, a vertical member pivotally connected to said tongue on a horizontal axis, roller means supporting said vertical member, said roller means being mounted on an axle set forward of a vertical line 15 dropped from said pivotal connection, and a pull connection secured to said vertical member at a point above a horizontal line extended forward from said pivotal connection.

2. In a wheeled toy the combination of a wagon body having a tongue, wheels beneath said body, a vertical member pivotally connected to said tongue on a horizontal axis, roller means sup-

porting said vertical member, said roller means being mounted on an axle set forward of a vertical line dropped from said pivotal connection, a pull connection secured to said vertical member at a point above a horizontal line extended forward from said pivotal connection, and a stop secured to said vertical member and adapted to engage the underside of said tongue when the pull connection has moved said vertical member into its maximum desired forward position.

3. In a wheeled toy, the combination of a platform mounted on a pair of wheels, an extension on said platform extending ahead of said wheels, a vertical member having the vertical side profile of an animate object, a roller support for said member, a pivotal connection between said extension and said vertical member, said connection lying aft of the vertical projection of the axis of said roller support, and a pull connection to said vertical member, said pull connection lying above the horizontal projection of the axis of said pivotal connection, whereby a forward pull on said connection will cause said vertical member to change its angular relation to said platform and upon release of said forward pull, said vertical member will fall back toward said platform.
